MAIL BOX

Filed April 2, 1924

UNITED STATES PATENT OFFICE.

SOL C. SHERRY, OF ENGLEWOOD, NEW JERSEY.

MAIL BOX.

Application filed April 2, 1924. Serial No. 703,682.

This invention relates to mail receptacles, and more especially to rural mail boxes.

It is the purpose of this invention to provide a mail box which will be especially suited to the conditions prevailing upon rural free delivery routes.

It is also an object of this invention to provide a mail box supplying in itself means for the reception of letters and packages, whether of such form as to pass through the ordinary mail slot or requiring a much larger opening.

A further purpose of this invention is to provide a mail box having provision for retaining money to pay for postage, and signal means for indicating when mail has been deposited in the box.

It is the especial object of this invention to provide all of the foregoing advantages in a single structure, constructed from sheet metal and able to withstand the abuse to which such receptacles are subjected.

In the accompanying drawings and in the appended description like numerals have been employed to indicate like parts.

Fig. 1 is an elevation of the complete device with the signal thereof at a raised position.

Figure 2 is a cross-sectional view of the device shown in Figure 1, taken vertically therethrough it.

Figure 3, shows a detail of the signal device.

Figure 4, shows in fragmentary detail a portion of the mail slot and door of the device shown in Figure 1.

Figure 5, is a sectional view of the device for the retention of coins which is shown in Figure 2, and is taken upon line 5—5 thereof.

Referring to the elevation shown in Figure 1, the box body is indicated by the numeral 10, the front cover or door by the numeral 12, the top cover or cap by the numeral 14 and the signal flag by the numeral 16.

Referring to Figure 2, it will be seen that the box body is substantially rectangular in form, having a closed back, bottom, sides and a front having an opening therein, normally closed by the door 12, which is here shown partially open. This door 12 will be seen to consist of a flat front portion, having an opening 20, near its upper end, which provides the mail slot for the reception of the letters and the like. Slot 20 is normally

closed by the gravity retained flap 22, which is offset as at 24 to engage the lower slot edge. The portion of the flap 22 which hangs external to the box and upon which the words U. S. Mail are preferably embossed serves as the necessary weight to retain the flap 22 in position of closure. The detail shown in Figure 4 more clearly illustrates the flap construction which has just been described and also shows the rearwardly turned edges 12^a, of the door 12, which embrace and frictionally contact with the sides of box 10, when door 12 is closed. These rearwardly turned portions 12^a, assist in keeping the elements from the interior of the box and serve in part to retain the door 12 closed. Door 12 is further retained by means of the latch member 26, which engages the body 10 above the front opening 20 therein. Door 12 is also provided with an outwardly turned hasp portion 28, which cooperates with a second hasp portion 30 upon the peaked cover 14. Cover 14 is pivoted to box 10 through such means as the rivets 32. It will be understood that cover 14 may be raised to insert a parcel or large envelope through the top of the box, if such cannot be readily inserted through the door 12. The cooperating hasps 30 and 28 permit a single padlock to be used if the box is to be locked and also provides for the insertion and removal of packages or letters of the maximum size without folding or distortion.

The rural free delivery man is often the only post office facility which the country dweller has access to. From him he must purchase his stamps and it is common practice to leave a coin with the letter which is to be collected in lieu of a stamp. The carrier supplying the stamp and affixing it to the letter. Such coins often become lost or removed by improper persons; for the protection of such coins I provide a coin safe 36 shown in Figure 2, and in greater detail in Figure 5.

The coin safe 36 consists of an outwardly inclined portion 38 affixed to the box side 10^a, by such means as the rivet 39. Portion 38 is provided with side flanges 41, which serve to retain the coin 42 and also as hinge points for the pins 44, which pivot the safe lid 45. The lid 45 is provided with an inwardly turned portion 46, having a downwardly turned lip 47. When the safe 36 is mounted as is shown in Figure 2, directly within the door 12, it is out of the

reach of any improperly accredited persons, and is at the same time readily accessible to the mail carrier. The carrier is often obliged to employ only one hand in manipulating the box and the safe 36 is especially designed for manipulation without the employment of both hands and without the removal of gloves, if such are worn. To release the coin it is merely necessary to engage the lip 47 with a portion of the hand and to move the lid 45 outwardly to the position indicated by the dotted lines of Figure 5. The coin 42 will drop downward into the palm of the hand below.

15 Referring to the signal (best seen in Figure 3) a flag 16 is preferably provided with a forwardly extending portion 16^a, and with a transversely extended portion 16^b. Flag 16 is supported by such means as a staff 50, 20 of flat sheet metal, having a slot 51 adjacent its lower end and engaging a pin 52, in a bearing member 53, affixed to the box side adjacent its top. Bearing member 53 may be provided with a closed back and as will be seen from Figure 3, it is necessary to first raise staff 50 upwardly so that it clears the back of bearing 53 before it may be turned to the horizontal, or non-indicating, position indicated by the dotted lines 55. With regard to the construction of bearing 53, it may be said that it is not essential that this bearing have an entirely closed back; a similar purpose may be accomplished by the two rivets 57, which engage the staff 50 to retain it vertical or horizontal at the will of the manipulator. This flag structure is especially suited to the exposed condition which such a device must occupy. It will be seen that the wind, or a chance blow, cannot effect 30 the setting of the flag and that a correct indication will be given regardless of the elements.

25 A further problem which is met in the erection of such mail boxes lies in so securing the box to a post or other supporting structure that it will remain rigid and unaffected by the natural deterioration of the post. I have furnished a solution of this problem by the provision of a three sided member 60 secured to the rear of box 10 by 40 means of rivets 61. This member 60 is preferably of flexible sheet metal and is adapted

to embrace the top and sides of a post 63 and to be secured thereto by means of screws or the like inserted through the holes 64. It 55 will be noted that this member 60 at once provides for securing the box to the post and for the protection of the end and top of the support.

60 It will be evident that the hereinbefore disclosed invention provides means which are at once simple, effective, and economical, and that the structure presented is especially adapted for the purposes for which it is designed, and offers no complicated structure, liable to become inoperative due to lack of attention or maintenance. Manifestly, changes and modifications may be made in the structure or in the elements thereof without departing from the spirit of my invention or from the scope of the appended claim.

70 Having thus described my invention, what I claim is new and desire to secure by Letters Patent is as follows:

75 In a mail box receptacle for coins, a body part having an outwardly inclined portion provided with side flanges projecting outwardly therefrom, a substantially flat section adjacent to and above said inclined portion, and a further portion at the end of said inclined portion and at substantially right angles to said flat section, said flat section being provided with receptacle holder reception means, said further portion serving to space the lower end of said inclined portion from the surface upon which the receptacle is held, said body part being provided with a lid part having a body portion provided with inwardly turned flanges on three sides and with an extension lip projecting from one of said flanges to provide a handle the other said flanges being perforated adjacent their innermost edges to engage a hinge pin 80 projecting through the outermost edges of the flanges on said body part so that the lid is normally held by its own weight over said body portion to form a complete coin receptacle which will discharge upon pulling 85 said lid lip.

90 Signed at New York in the county of New York and State of New York this 29th day of March, A. D. 1924.

100 SOL C. SHERRY.
